UNITED STATES PATENT OFFICE

ISAAC A. BAUM, OF CHICAGO, ILLINOIS

FRAMING AND TRIM FOR ALL-PLASTER WALLS

Application filed February 21, 1929, Serial No. 341,742. Renewed January 6, 1930.

My invention relates to door frames and particularly to a frame for all-plaster walls.

It has been found to be desirable in interior construction to build walls entirely of plaster, thus economizing in space. A construction of this character is illustrated in my co-pending applications Ser. No. 259,433 filed March 6, 1928, and Ser. No. 285,268 filed June 14, 1928.

However, in the construction heretofore proposed, a wood jamb and trim has been contemplated, and, due to the narrow space, this has involved some difficulty. Furthermore, in fire-proof buildings, it is desirable to eliminate wood portions of the frame if possible. I have therefore devised and herein described a combined buck, jamb and trim of simple form and economical construction. The complete frame is adapted to be assembled in the shop and installed with a minimum of labor and without the use of metal-working appliances.

The invention will be more readily understood by reference to the accompanying drawings, in which

Fig. 1 is an elevation of a frame arranged in accordance with my invention;

Fig. 2 is a sectional view, somewhat enlarged, through the frame; and

Fig. 3 is an enlarged fragmentary elevation of one corner.

In the drawings, I have illustrated side frames A, B, and the head frame C all of duplicate cross-section. A sectional view is shown in Fig. 2 the section being taken at the point 2-2 of Fig. 1 from which it will be seen that the main frame element or buck consists of a channel member having side flanges 10 and a web 11. The side flanges at 12 and the marginal portions 13 are angularly disposed and preferably rebent as shown. Suitable openings such as 14, 15 are provided at intervals to serve as plaster keys and as the means for attachment of wire lath 16 by means of the twisted wire 17.

The jamb and trim elements comprise a strip of metal bent to provide a flat portion 18 acting as a jamb, a portion 19 constituting a stop and decorative portions 20-21 that serve as trim. Portions 22, 23 project inwardly from the edges of the trim and are bent to provide shoulders 24, 25 that serve as plaster grounds. The marginal portions 26, 27 are bent to lie parallel to the margins 13 and welded thereto as indicated. The interlocking arrangement shown insures proper assembly prior to welding.

The parts described are completed in the factory and shipped to the job in the form indicated. As a means for assisting in erecting I provide the channel members 28 telescoped within the channel buck and welded thereto, the extensions having feet 29 at the upper ends to enable the parts to be secured to the ceiling. Similar flanges 30 are provided at the bottom for securing the lower ends of the frames to the floor.

A construction such as described adapts itself readily to interior construction and is cheap and efficient for the purpose.

I claim:

1. In combination, side and head frame elements in the form of deep, narrow channels in cross section, the margins of the channels being angularly disposed relative to the flanges of the channels and a combined jamb and trim having its marginal edges bent to engage with and be secured to the margins of the channels.

2. In combination, frame members of channel shape with the edges of the flanges bent at an angle, and a strip of metal bent to form a combined jamb, stop and trim with the edges of the strip projecting inwardly to contact with and be secured to the angular edges of the flanges.

3. In combination, frame members of channel shape with the edges of the flanges bent at an angle, and a strip of metal bent to form a combined jamb, stop and trim with the

edges of the strip projecting inwardly to contact with and be secured to the angular edges of the flanges, and means on the strip for providing a plaster ground.

4. In a door frame for all plaster walls, the combination of a narrow channel with the flanges projecting toward the door opening, the margins of the flanges being disposed at an angle to the flanges, and a hollow metal member constituting a jamb and trim, the margins of the metal member projecting inwardly and being welded to the margins of the flanges of the channel.

In testimony whereof I have affixed my
signature.

ISAAC A. BAUM.
